UNITED STATES PATENT OFFICE.

CHARLES MOE, OF CHICAGO, ILLINOIS.

GEM-DISPLAYING RING.

No. 873,156.

Specification of Letters Patent.

Patented Dec. 10, 1907.

Application filed October 1, 1906. Serial No. 336,950.

To all whom it may concern:

Be it known that I, CHARLES MOE, a citizen of the United States of America, and a resident of Chicago, in the county of Cook and State of Illinois, have invented certain new and useful Improvements in Gem-Displaying Rings, of which the following is a specification.

This invention relates to gem displaying rings, for use by retail jewelers, and has for its object to provide a simple and efficient structural formation and combination of parts adapted to readily and rapidly receive different sizes of gems, and display the same in a manner equal to a regular setting, all as will hereinafter more fully appear.

In the accompanying drawings:—Figure 1 is a perspective view of the present improved display ring. Figs. 2 and 3 are side elevations of the same illustrating the same holding different sizes of gems.

Similar numerals of reference indicate like parts in the different views.

Referring to the drawings, 1 represents a ring formed of a suitable resilient material and which is formed with a cut or opening 2 in its wall, so that the ends formed by said cut may be forcibly spread apart against the normal resilient tendency of the material 30 forming the ring to hold such ends together.

3 are holding prongs, similar to those used in gem settings and which are arranged in

opposed relation on the respective ends, as shown in the drawing.

In actual use the respective ends of the 35 ring carrying the holding prongs aforesaid, will be spread apart sufficiently to receive the gem to be displayed, and then allowed to close upon and hold the same in place under the resilient stress of the main portion of the 40 ring. So constructed and arranged the present ring affords all the appearance of an ordinary ring setting for displaying gems, while at the same time permitting of a rapid removal and replacement of different sizes and 45 qualities of gems as the purchaser proceeds with making a collection.

Having thus fully described my said invention, what I claim as new and desire to secure by Letters Patent, is:—

A display ring for jewelers, the same comprising an open circle of resilient material provided with opposed gem holding prongs at the respective sides of its open portion, said holding prongs being normally in close 55 relation and requiring to be sprung apart in order to receive and have holding engagement with a gem.

Signed at Chicago, Illinois, this 29th day of September 1906.

CHARLES MOE.
